UNITED STATES PATENT OFFICE

155,896

DESIGN FOR A ROLL PRESS END OR SIMILAR ARTICLE

Lloyd Hornbostel, Beloit, Wis., assignor to Beloit
Iron Works, Beloit, Wis., a corporation of Wis-
consin

Application February 19, 1948, Serial No. 144,608

Term of patent 14 years

(Cl. D63—1)

To all whom it may concern:

Be it known that I, Lloyd Hornbostel, a citizen of the United States and a resident of the city of Beloit, in the county of Rock and State of Wisconsin, have invented a new, original, and ornamental Design for a Roll Press End or Similar Article, of which the following is a specification, reference being had to the accompanying drawings, forming a part thereof.

On the drawing:

Figure 1 is a perspective view of the roll press end taken from one side embodying my new design.

Figure 2 is an elevational view of the other side of the roll press end.

I claim:

The ornamental design for a roll press end or similar article, as shown.

LLOYD HORNBOSTEL.
